PULSE-ECHO CONTROL SYSTEM

Alda V. Bedford, Princeton, N. J., assignor to
 Radio Corporation of America, a corporation
 of Delaware

Application October 19, 1942, Serial No. 462,644

12 Claims. (Cl. 250—1.54)

1

My invention relates to pulse-echo systems and particularly to systems wherein an antenna system and/or guns or the like are moved automatically to a position determined by the location of an object relative to the radiation pattern of the antenna system. The invention will be described specifically as applied to a radio pulse-echo system wherein the transmitter radiates signals from antennas having overlapping directional radiation patterns.

An object of the invention is to provide an improved system of the above-mentioned type.

A further object of the invention is to provide an improved system for aiming guns at an object automatically in accordance with its location with respect to overlapping radiation patterns.

A still further object of the invention is to provide an improved system for producing control signals in accordance with the location of an object with respect to overlapping radiation patterns.

A still further object of the invention is to provide an improved system of the above-mentioned type which employs an alternating-current drive.

In a preferred embodiment the invention is applied to a pulse-echo system having a directive antenna system so designed that its radiation pattern or patterns may be rotated in both a horizontal plane and a vertical plane to search for an object such as an enemy airplane. The antenna system may consist of four directive antennas which may be keyed successively, as described, for example, in Patent No. 2,412,702, issued on December 17, 1946, in the name of Irving Wolff, and entitled Object detection and location, or an antenna system may be employed which is keyed by means of shorting condensers as described and claimed in Patent No. 2,400,736, issued on May 21, 1946, in the name of George H. Brown, and entitled Antenna systems.

In the receiver, control signals are derived from the four groups of pulses that have been reflected successively from the target or other object as the antennas are keyed. These groups of pulses, after demodulation, are applied to a peak measuring circuit that is switched alternately to amplifier tubes having storage capacitors in their input circuits. This switching is in synchronism with the keying of the directive antennas. The received pulses of one group charge their respective capacitors to potentials having values depending on the pulse amplitude and the control grids of said amplifier tubes are held at these capacitor potentials until the next group of pulses is applied. As a result, square wave voltages

2

appear in the amplifier tube output circuit which are connected to suitable A.-C. amplifiers. Alternating currents of sine wave form appear in the A.-C. amplifier output circuits. These currents are supplied to reversible A.-C. motors for positioning the antenna system and/or the guns or other units to be controlled. As will be explained hereinafter, the phase of the square wave voltage and of the sine wave current is determined by the relative amplitudes of the received reflected pulses in the two horizontal radiation patterns and by the relative amplitudes of the received reflected pulses in the two vertical radiation patterns. The A.-C. output of each amplifier has one phase relation if the center of the radiation pattern is on one side of the target and it has the opposite phase relation if said center is on the other side of the target. Therefore, the A.-C. motor for either train or elevation control will reverse if the center of the radiation pattern for the corresponding pair of antennas swings from one side of the target to the other side. When the center of the radiation pattern is on the target, the A.-C. supplied to the motor is zero and the motor stops.

The invention will be better understood from the following description taken in connection with the accompanying drawing in which

Figure 1 is a circuit diagram of one of the preferred embodiments of my invention; Figure 2 is a diagram of the radiation patterns of the directive antennas employed in the system of Fig. 1; and

Figures 3 to 8 are graphs that are referred to in explaining the invention. In the several figures like parts are indicated by the same reference characters.

Figure 1 shows a radio pulse-echo system comprising four directive antennas 10, 11, 12 and 13 for radiating the pulse energy slightly upward, downward, to the right and to the left, respectively, with respect to a central common axis, as indicated by the letters U, D, R and L. To simplify the drawing, these antennas are shown as dipoles having parabolic reflectors. The radiation patterns for these antennas are overlapping conical patterns of the character indicated in Fig. 2 where the patterns marked U, R, D and L correspond to the antennas similarly marked in Fig. 1. It is understood that the antenna radiation is greatest in the axis and weakens toward the surface of each of the cones. The antennas 10, 11, 12 and 13 may be like those illustrated in the above-mentioned Wolff or Brown patents, or of any suitable type, and in the particular sys-

tem being described are mounted on a gimbal so that they may be moved to make their radiation patterns scan both horizontally and vertically.

High frequency radio pulses are supplied successively to the U, R, D and L antennas from a transmitter 16 through cam operated switches 17, 18, 19 and 21, respectively, driven by a synchronous motor 22. The said pulses are obtained by modulating the high frequency carrier wave produced at transmitter 16 by means of keying pulses from a source 23. The source 23 may be a multivibrator supplying pulses recurring at the rate of 4.1 kilocycles per second, for example.

The receiver 24 demodulates the reflected pulses of high frequency (4.1 kc. in the example assumed) energy to supply pulses 27 to a detector or rectifier 26 which preferably is of the peak rectifying type. The tube 26 may be biased beyond cut-off by a battery 25 as illustrated or it may be grid-leak biased to provide peak detector action as is well known in the television art. The output of rectifier 26 is supplied through a large capacity blocking capacitor 31 and a switch 32 to capacitors 38 and 39, respectively, connected across the input circuits of amplifier tubes 43 and 44. The switch 32 comprises commutator segments 33, 34, 36 and 37 and brushes 41 and 42. The output from rectifier 26 is represented by the graph 51 where the four groups of filtered or integrated pulses of unequal amplitude are indicated at U, R, D, L. The same output as it appears on the other side of capacitor 31 is shown in Fig. 3.

The anode circuits of the tubes 43 and 44 are connected to A.-C. amplifiers 53 and 54 which drive A.-C. motors 61 and 62, respectively, in the particular example illustrated. These motors rotate in one direction or the other when the radiation pattern is off the target and stop when it is on the target, as will be explained in connection with Figs. 3 to 8. As indicated by the legends, motors 61 and 62 are mechanically coupled to the elevation controlling and train controlling shafts 63 and 64, respectively, of the antenna supporting gimbal whereby the antenna radiation pattern is made to follow automatically an airplane or other object. The motors 61 and 62 may also control the elevation and train of one or more guns or search lights (not shown) whereby they are held on the airplane or other target automatically by means including the described servo system.

The switch 32 is driven by the motor 22 in synchronism with the antenna cam switches 17, 18, 19 and 21. Thus, in the diagram the "up" antenna switch 17 is closed, the corresponding switch segment 33 of the control circuit is in contact with brush 41 to complete a circuit to the tube 43 and all other switch segments are out of contact with the brushes. Next, as the switch 32 is rotated, the cam switch 18 closes and the segment 34 comes into contact with brush 42 to complete a circuit to the tube 44. The switching sequence in this particular example is U, R, D, L as will be apparent from the shape of the cams and from the direction of rotation indicated by the arrows. The complete switching cycle may occupy $1/60$ second, for example.

The particular graph shown at 51 represents a condition where the radiation pattern of the antenna system is not centered on the target. It will be noted that the group of reflected pulses during the interval U are of greater amplitude than during the interval D, and that during the

interval R they are of less amplitude than during the interval L. During the time segment 33 is in contact with brush 41, the capacitor 38 is charged to a voltage equal to the peak voltage of the U group of reflected pulses; after the segment 33 rotates out of contact with the brush 41 the capacitor 38 retains this charge. When segment 33 next comes into contact with the brush 41, the capacitor 38 either acquires more charge or loses some charge if the peak amplitude of the pulses has changed. Similarly, the other capacitor 39 is charged by the received pulses so that the voltage thereacross corresponds to the peak amplitudes of the pulses in groups R and L. The switch segments 33, 34, 36 and 37 preferably make contact with the brushes shortly after the beginning of intervals U, R, D and L of graph 51, respectively, and break contact shortly before the end thereof. It may be noted that the time scales for graphs 51 and 27 differ greatly, the pulse 27 actually being very short compared with the interval U, for instance.

The application of the pulse groups U and D to the amplifier tube 43 produces the square-wave voltage 45 (Fig. 4) which appears at the anode of this tube. It will be noted that because of the stored signal in capacitor 38, the positive portion of the wave 45 produced by the U group of pulses holds over until the D group of pulses occur, this being a feature that is desirable but not essential to the operation of my system. The negative portion likewise holds over until the next group of U pulses occurs. Similarly, the application of the pulse groups R and L to the amplifier tube 44 produces the square-wave voltage 50 (Fig. 5) which appears at the anode of this tube. The square-wave voltages 45 and 50 appear in the output circuits of amplifiers 53 and 54 substantially as the sine wave voltages or currents indicated by the broken line curves 45a (Fig. 4) and 50a (Fig. 5), respectively. These sine wave voltages or currents drive the motors 61 and 62 in one direction or the other depending upon the phase of the voltage since the A.-C. field supply is synchronous with the A.-C. current supplied to the motor armatures.

Assume that the location of the target or other reflecting object with respect to the antenna radiation pattern is such that the four groups of pulses supplied to the switch 32 are as shown in Fig. 6. Now the U and D groups produce the square wave signal 55 as shown in Fig. 7 to supply the sine wave voltage 55a to the motor 61. It will be noted that the voltage 55a is 180 degrees out of phase with the voltage 45a previously supplied to motor 61. Thus the change from the signal of Fig. 3 to that of Fig. 6 reverses motor 61. By means of this action the antenna system is adjusted about its elevation control axis until the radiation pattern is centered vertically with respect to the target.

The R and L groups of Fig. 6 produce the square-wave voltage 60 and the sine wave voltage 60a of Fig. 8. In this particular example, the voltage 60a supplied to motor 62 is 180 degrees out of phase with respect to the voltage 50a previously applied to the motor whereby the motor 62 reverses. Thus the antenna system is adjusted about the train control axis 64 until the radiation pattern is centered horizontally with respect to the target.

An important feature of the invention is that the system is not affected much by noise signals because the capacity of the capacitors 38 and 39 is so large that their charge is changed a negligible

amount by such signals. Expressed another way, the capacitors reduce the noise by reducing the net band-width of the signal used. However, the time constant must not be made too long or hunting of the servo system may occur due to the delay of the signal.

It should be understood that the invention is not limited to a system employing four radiation patterns as it is equally applicable, for example, to a system having only left-right control or indication. Also, the radiation patterns may be produced by sound or light radiation, for example, rather than by radiation of radio signals, my capacitor-switching receiving system being equally applicable to all such systems.

I claim as my invention:

1. In a servo system, means for transmitting pulses and receiving echoes alternately for short intervals from an assembly of two directive radiators, said radiators being assembled so the received signal differs in strength for the two intervals in accordance with the displacement of the assembly of radiators with respect to the source of the echoes, a capacitor, switching means synchronized with the transmitting and receiving means for charging the capacitor successively in accordance with the received signal during the intervals of utilization of one of the radiators and during the intervals of utilization of the other radiator, an electric motor, and utilizing means for driving said motor backward or forward in accordance with the relative amplitudes of the voltages appearing successively across said condenser, and means whereby said motor turns said assembly of radiators toward said source of echoes.

2. In a system wherein groups of pulses are received alternately, a vacuum tube having a capacitor connected across its input electrodes, switching means associated with said capacitor, means for passing direct current pulses representative of said alternately-occurring groups of pulses only through said switching means to charge said capacitor whereby a substantially square wave voltage appears thereacross, means for making said switching means effective to pass current to said capacitor synchronously with the reception of said groups of pulses, an electric motor of the type that reverses when an alternating current applied thereto is reversed in phase, an alternating current amplifier connected to said motor to supply alternating current thereto, and means for supplying said square wave voltage to said amplifier.

3. In a receiver for receiving reflected pulses in a system wherein pulses of energy are transmitted in a pair of overlapping radiation patterns, each pattern including a group of pulses, the said radiation patterns being radiated in succession, means for obtaining from said reflected pulses a signal having repeating voltage levels, a capacitor, a vacuum tube having input electrodes connected across said capacitor, means for connecting said first means to the input electrodes of said vacuum tube, said connection being made in synchronism with and only during the radiation of said pair of patterns whereby a square wave voltage appears across said capacitor, an alternating current motor of the type that reverses when alternating current applied thereto is reversed in phase, and means for applying the fundamental frequency component of said square wave voltage to said motor.

4. In a radio pulse echo system, a pair of directive antennas having overlapping radiation

patterns, a radio pulse transmitter, means for switching said antennas successively to said transmitter whereby pulses are radiated to a reflecting object, a receiver for receiving pulses reflected from said object, a capacitor, switching means for successively applying said received pulses to said capacitor for producing a square wave voltage thereacross, an alternating current motor of the type that reverses when the alternating current supplied thereto is reversed in phase, means for amplifying the fundamental frequency component of said square wave voltage, and means for driving said motor by said amplified voltage.

5. In a radio pulse echo system, a pair of directive antennas having overlapping radiation patterns, a radio pulse transmitter, means for switching said antennas successively to said transmitter, a receiver including means for obtaining a voltage that is a measure of the amplitude of the group of reflected pulses of one radiation pattern and for obtaining a voltage that is a measure of the amplitude of the group of reflected pulses of the other radiation pattern, a capacitor, switching means for successively applying said two voltages only to said capacitor for producing a square wave voltage thereacross, an alternating current motor of the type that reverses when the alternating current supplied thereto is reversed in phase, means for amplifying said square wave voltage, and means for driving said motor by said amplified voltage.

6. In a radio pulse-echo system, a pair of directive antennas having overlapping radiation patterns, means comprising a radio transmitter for transmitting in each pattern a group of pulses, means for switching said antennas successively to said transmitter, a receiver, means for obtaining two voltages which are a measure of the amplitude of the two groups of reflected pulses, respectively, a capacitor, switching means for successively applying said two voltages only to said capacitor for producing substantially a square wave voltage thereacross, an alternating current motor of the type that reverses when the alternating current supplied thereto is reversed in phase, means for amplifying said square wave voltage, and means for driving said motor by said amplified voltage.

7. In a pulse-echo servo system, an assembly of radiators, means for producing an alternating-current wave consisting of four repeating voltage levels having amplitudes corresponding inversely to the angular displacement of said assembly of radiators from a reflecting target in the directions upward in the vertical plane, to the right in the horizontal plane, downward and to the left, respectively, an amplifier, synchronous switching means for connecting said source of alternating-current wave to said amplifier only during the time of the voltage levels corresponding to said displacements in one of said planes, a reversible alternating-current motor having an alternating-current field supply synchronous with said alternating-current wave, and means for supplying the output of said amplifier to said motor, said motor being mechanically coupled to said assembly of radiators to turn it toward said target.

8. In a pulse-echo servo system, an assembly of radiators, means for producing an alternating-current wave consisting of four repeating voltage levels having amplitudes corresponding inversely to the angular displacement of said assembly of radiators from a reflecting target in the directions

upward in the vertical plane, to the right in the horizontal plane, downward and to the left, respectively, a capacitor, synchronous switching means for connecting said source of alternating-current wave across said capacitor only during the time of the voltage levels corresponding to said displacements in one of said planes, a reversible alternating-current motor having an alternating-current field supply synchronous with said alternating-current wave, and means for amplifying the fundamental alternating-current component of voltage across said capacitor and applying said voltage to said motor, said motor being mechanically coupled to said assembly of radiators to turn it toward said target.

9. In a pulse-echo servo system, an assembly of radiators, means for producing an alternating-current wave consisting of four repeating voltage levels having amplitudes corresponding inversely to the angular displacement of said assembly of radiators from a reflecting target in the directions upward, to the right, downward and to the left, respectively, a capacitor, synchronous switching means for connecting said source of alternating-current wave across said capacitor only during the time of the voltage levels corresponding to said displacements to the right and to the left, a reversible alternating-current motor having an alternating-current field supply synchronous with said alternating-current wave, and means for amplifying the fundamental alternating-current component of voltage across said capacitor and applying said voltage to said motor, said motor being mechanically coupled to said assembly of radiators to turn it toward said target.

10. In combination, a pair of alternating current motors of the type that reverses when alternating current applied thereto is reversed in phase, means for obtaining alternately occurring first and second voltages each having an amplitude with respect to ground potential representative of the direction in which it is desired to drive one of said motors, means for obtaining alternately occurring third and fourth voltages each having an amplitude with respect to ground potential representative of the direction in which it is desired to drive the second motor, said voltages occurring in the sequence of first, third, second and fourth voltages, means for amplifying the fundamental frequency component of the alternating-current wave formed by said first and second voltages to the exclusion of said third and fourth voltages to obtain alternating current, means for applying said alternating current to said first motor, means for amplifying the fundamental frequency component of the alternating-current wave formed by said third and fourth voltages to the exclusion of said first and second voltages to obtain a second alternating current, and means for applying said second alternating current to said second motor.

11. In a radio pulse-echo system, a receiver, an assembly of directive antennas having overlapping radiation patterns in the horizontal plane and having overlapping radiation patterns in the vertical plane, means for switching said antennas successively for supplying to said receiver an alternating-current wave consisting of four repeating voltage levels corresponding inversely in amplitude to the amount of angular displacement of said assembly from a reflecting target in four directions, respectively, an amplifier, switching means for successively applying said alternating-current wave to said amplifier only during the time of the two voltage levels corresponding to angular displacement in the horizontal plane, a second amplifier, switching means for successively applying said alternating-current wave to said second amplifier only during the time of the other two voltage levels, a pair of alternating current motors connected to receive current from said first and second amplifiers, respectively, said motors being of the type that reverses when the alternating current supplied thereto is reversed in phase.
12. In a servo system, means for transmitting pulses from an assembly of directive radiation means for radiating successively overlapping radiation patterns in a horizontal plane and in a vertical plane, means for receiving said pulses after reflection from an echo source, said radiation patterns having characteristics such that the received signal differs in strength for the successive radiations in accordance with the displacement of the assembly of the radiation means with respect to the source of the echoes, two capacitors, switching means synchronized with the transmitting and receiving means for charging each of said capacitors in accordance with the received signals during the interval of transmission by radiation in each of said planes, respectively, two alternating current motors, and utilizing means for driving each of said motors backward or forward in accordance with the phase of the voltage across each of said capacitors, respectively, and means whereby said motors turn said assembly of radiators toward said source of echoes.
